UNITED STATES PATENT OFFICE

LEO GOLDHAMMER, OF MUNICH, GERMANY, ASSIGNOR TO AGFA ANSCO CORPORATION, OF BINGHAMTON, NEW YORK, A CORPORATION OF NEW YORK

PHOTOGRAPHIC SHUTTER

Application filed October 8, 1929, Serial No. 398,948, and in Germany October 8, 1928.

My present invention relates to photographic shutters and more particularly to shutters, the blades of which are automatically tensioned and released by pulling the operating lever downwardly.

One of its objects relates to the bearing of the operating lever of the shutter.

Another object of my invention is to coordinate the operating lever with the spring actuated shutter blades in such a manner that the shutter is tensioned and opened directly by a cam on another part of the operating lever.

A still further object of my invention is to provide an operating lever which when adjusting the shutter to "time", opens directly the locking device of the blades, without need of a separate lever as hitherto required.

Other objects and advantages in details of construction and operation will be apparent as the description proceeds reference being had to the accompanying drawing wherein like reference numerals indicate like parts.

Fig. 1 is an interior view of my shutter.

Fig. 2 is a view similar to Fig. 1 showing the shutter parts in a position they occupy when tensioned ready for exposure with closed blades.

Fig. 3 is a view similar to Figs. 1 and 2 illustrating the shutter while effecting instantaneous exposure.

Fig. 4, likewise, is a view similar to Figs. 1 and 2 illustrating the shutter while effecting time exposure.

Fig. 5 shows in detail the operating lever removed from the shutter casing.

Referring more particularly to the illustrated embodiment of my invention, 1 illustrates an annular plate with a surrounding angular flange interrupted at 1' to form an opening for the arm 6 of the operating lever. The bottom plate 1 of the shutter casing is provided with a central opening 3 surrounded by an interior cylindrical flange 2 bent out from intermediate pieces 4, partly covering the plate 1.

The operating lever shown in detail in Fig. 5 comprises an arm 6 and a plate 5 with curved margins and with an annular

opening capable to embrace the cylindrical flange 2 of the bottom plate of the shutter casing. Thus, the operating lever can be pivoted upon the flange 2. By holders 7 secured to the intermediate plates and engaging with bayonet-like slotways 8 of the plate 5, the annular operating lever is secured in its rotary position. By a spring 9 anchored with one end to the casing, it is held in its initial position shown in Fig. 1.

10 and 11 are the shutter blades. The blade 10 is rotary mounted on the blade 11 with a pin 12, while the blade 11 is pivoted on a pin 13 in the shutter casing. Springs 14 and 15 tend always to hold the blades 10 and 11 in the closed position seen in Fig. 1. The blade 10 is provided with a bent lap 16, which strikes an angular shoulder 17 of the blade 11, if the shutter is closed.

On the annular operating lever 5, a cam 18 is fitted so as to be rotary round a bolt 19. The external edge of the said cam 18 is bent rectangularly, so that a flap 20 of the cam projects backwards and abuts against a pin 21 mounted on the blade 11, when the operating lever is turned. The cam 18 is pressed against the cylinder wall 2 by the action of the spring 22.

23 is a locking lever or ratchet pivoted in the shutter casing and pressed by the spring 24 against the pin 25. The pin 25 is connected with a regulating device outside the shutter and may be moved to and fro radially in the shutter casing, whereby the position of the ratchet 23 is altered. From the ratchet 23 a pin 26 projects through a slit provided in the intermediate piece 4, so that it may come in contact with the curved margin 27 of the operating lever 5.

The shutter operates as follows:

In normal position, all parts of the shutter are situated as seen in Fig. 1. If the operating arm 6 is depressed downwards, the plate 5 and the cam 18 connected therewith are turned round the central flange 2 surrounding the shutter opening 3. The free end 20 comes in contact with the pin 21 and thus swings the shutter blade 11 about its pivot 13. The shutter blade 10, being pivoted on the blade 11 and striking with its bent

lap 16 against the angular shoulder 17 of the blade 11, performs the same swinging movement. Both shutter blades 10 and 11, partly covering each other, pass the objective opening 3. This movement tensions the springs 14, 15 and 9, likewise. The edged shoulder 16 of the blade 10 slides along the ratchet 23 and erects it. At the most extreme tension of the shutter, it has passed the ratchet 14, the latter is pressed downwards by the spring 24, as far as allowed by the adjustable pin 25 and thus the shutter blade 10 is retained in engagement with the nose at the front part of the ratchet 24, while the blade 11 strikes with its angular shoulder 17 the bent lap 16 of blade 10. This is shown in Fig. 2.

The exposure now is accomplished through a further movement of the operating arm 6 in downward direction, by which the nose 20 of the cam 18 slides away from the pin 21 and sets it and therewith the shutter blade 11 free. The blade 11 swings back in its initial position by the action of the spring 14, whereupon the pivot 12 performs a circular way on account of its eccentric position regarding the pivot 13. Thereby, the blade 10 undergoes a downward movement and the shoulder 16 of the blade 10 slides away from the nose of the ratchet 23 until it leaves the action of the latter and snaps back by the action of the spring 15 in its initial position. Fig. 3 shows the shutter while the objective opening is partly opened for instantaneous exposure.

35 The duration of exposure, obviously, is influenced by the placing of the ratchet 23. If the pin 25 influences the ratchet 23 to strike only partly the shoulder 16, the blade 10 snaps back before blade 11 has completed its 40 return movement. If the blades have returned to their original position, the operating plate 5 connected with the arm 6 becomes free and swings back together with the cam 18 in the position shown in Fig. 1 by the 45 action of spring 9.

In the case of time exposure, the ratchet 23 is caused by a suitable adjustment of the pin 25 to engage the shoulder 16 of blade 10, if the arm 6 is completely depressed, to such 50 a degree that the length of its engagement is greater than the downward movement of the blade 10. Thus, the blade 11 remains arrested in its position giving free the exposure opening until the arm 6 is allowed to 55 return in its initial position. Then the curvature 27 strikes the pin 26 of the ratchet 23, erects the latter and sets free the blade 10, which now, likewise, snaps back and closes the objective opening.

60 By the specific form and bearing of the operating lever the tension and operation of the shutter blades is effected in a simple manner and the number of intermediate parts and levers is diminished, a part of the operating lever acting directly on the shutter blades.

Such a shutter on account of its simple construction can be manufactured at low cost and operates exactly.

What I claim is:

1. A photographic shutter comprising in operative combination a casing with a central exposure opening, blades, and means for making instantaneous and time exposures; said means including a speed controlling element for said blades, an operating lever rotatably mounted concentrically to the exposure opening, and means mounted on said operating lever for tensioning and releasing the shutter blades automatically and directly. 70

2. A photographic shutter comprising in operative combination a casing with a central exposure opening, blades and means for making instantaneous and time exposures; said means including a speed controlling element for said blades, an operating lever rotatably mounted concentrically to the exposure opening, a spring holding the operating lever in its initial position and means mounted on said operating lever for tensioning and releasing the shutter blades automatically and 80 directly. 85

3. A photographic shutter comprising in operative combination a casing with a central exposure opening, blades and means for making instantaneous and time exposures; said means including a speed controlling element for said blades, an operating lever rotatably mounted concentrically to the exposure opening, a spring holding the operating lever in its initial position, a pivoted cam 95 mounted on said operating lever and means for causing said cam to tension and to release the shutter blades automatically and 100 directly.

4. A photographic shutter comprising in operative combination a casing with a central exposure opening, means for making instantaneous and time exposures; said means including an operating lever rotatably mounted concentrically to the exposure opening, a shutter blade pivoted in the shutter casing, a second shutter blade pivoted upon the first shutter blade, springs for holding the blades in closed position, a cam mounted on the operating lever and means for causing said cam to tension and to release successively the said shutter blades directly and automatically. 110

5. A photographic shutter comprising in operative combination a casing with a central exposure opening, means for making instantaneous and time exposures; said means including an operating lever rotatably mounted concentrically to the exposure opening, a shutter blade pivoted in the shutter casing, a second shutter blade pivoted upon the first shutter blade, springs for holding the blades in closed position, a cam mounted on the operating lever, means for causing said cam to tension and to release successively the said 120 125 130

shutter blades directly and automatically, and means on the operating lever for unlocking the blades pivoted in the shutter casing in time exposure during the return movement of the operating lever in its initial position.

5 In testimony whereof, I affix my signature.

LEO GOLDHAMMER.
